UNITED STATES PATENT OFFICE.

FRANK HERNAMAN COTHAY, OF SUSSEX, ENGLAND, ASSIGNOR OF ONE-HALF TO ROPP TIN LIMITED, OF LONDON, E. C. 2, ENGLAND, A BRITISH COMPANY.

GRAVITY CONCENTRATOR FOR ORES.

Application filed August 18, 1924, Serial No. 722,723, and in Great Britain May 14, 1924.

This invention is for improvements in or relating to gravity concentrators and has reference to the type used generally in the treatment of alluvium-containing values in the form of tin-stone and comprising an inclined rectangular sluice or trough provided at intervals of every few feet with cross riffles. The alluvium collects behind the riffles to a depth equal to the height of the riffle, which may be several inches, while a stream of spoil or pulp is flowing through the sluice. Tin-stone out of the pulp sinks into the bed of material while the lighter materials pass over. Difficulty is encountered however in that the bed tends to become consolidated so that tin-stone cannot properly sink into it, but passes over the riffles and on down the sluice. Attempts to prevent this by raking are only partially successful. The prongs of rakes affect the material only along certain lines and cause channels, particularly if they are mechanically worked. Hand shovels can be used but it is desirable to have a mechanical device which will secure continuous and uniform agitation.

According to the present invention there is provided in a gravity concentrator, the combination of an inclined concentrating sluice, riffles therein extending across the sluice, agitating elements which are of less depth than the riffles and which extend across the sluice close to the bottom thereof between the riffles, and means to reciprocate the agitating elements along the sluice so that material collected in the pockets formed by the riffles is prevented from compacting without being stirred up.

The agitator may consist of a band of segmental cross-section, the flat face of the band being lowermost.

The action of the agitator is to disturb the material gently to prevent it caking and to allow the heavier tin-stone to settle through it. The superincumbent stratum of material above the wire is gently pulsated throughout its substance and kept uniformly loose, so that it affords an easy entry for the heavier values.

The accompanying drawing illustrates by way of example one form of concentrator embodying the invention. In the drawing—

Figure 1 is a vertical longitudinal section through the apparatus.

Figure 2 is a vertical transverse section therethrough and

Figure 3 is a cross-section of a certain part of the apparatus, shown on a larger scale than that of the other figures.

Like reference characters indicate like parts in the various figures.

The apparatus comprises several (preferably three or four) sluices 1, arranged side by side. These are made of sheet metal and are of considerable size. They may be about 100 feet long. The sluices are moreover provided with cross-riffles 2 at intervals of, say, every 8 feet, and they are set at a slight slope by being mounted in a pivoted cradle (not shown), the inclination of which can be suitably adjusted.

In each sluice is a series of agitating frames. These comprise longitudinal members 3 to which are secured cross-members 4 of flat steel bar which are bent downwardly at their ends. The bottom ends of the cross-members 4 nearly touch the bottom of the trough and between the two ends of each of them is stretched tightly a steel wire 5 which is segmental in cross-section, being flat on its underface and rounded at its upper face, so that the general section of the wire is elongated in the direction of the length of the sluice. This wire constitutes what is sometimes referred to in this specification as the agitator of the apparatus. The thickness of the wire may be about one quarter of an inch, and the breadth, say, about one inch. The wires 5 are of a sufficient length to extend completely across the trough 1 and the bent-down ends of the steel members 4 which carry them lie close to the sides of the trough so as not to interfere with the bed of material 6 which collects therein. The bent-down ends of the cross-members 4 are of such a depth that the cross-members and the longitudinals 3 which carry them are clear of the material 6 within the trough.

The frames are reciprocated slowly, say, at 10 or 15 double strokes a minute and the length of the stroke, which may be, say, about 18 inches, is so related to the distance between adjacent wires that the whole surface of the trough is traversed by the wires. The frames are supported from an overhead structure 7 by rigid links 8, which may, if desired, be adjustable in length.

Mechanism for reciprocating the frame may comprise at each side, a crank 9, rotatable at the required rate, about an axis disposed transverse to the frame. The pin of

2
this crank may be connected, by a simple system of links and cranks 10, to a pivotal connection to the longitudinal member 3 of the frame, the said system of cranks and links being such that rotation of the crank 9 will occasion reciprocation of the frame, with the required stroke.

In operation the pulp or slurry of alluvium is directed into the troughs 1, flows 10 therethrough by gravity and deposits a bed of alluvium in each trough against the riffles. This bed of alluvium overlies the agitating wires 5 and is prevented from caking by the reciprocation of the wires which, 15 while not disturbing the material unduly, yet keeps it all loose, so that the heavier valuable particles may sink into and through the bed, while the lighter gangue particles are washed away.

10 The apparatus may be mounted upon a dredging barge so that alluvium recovered from the bed of a river may be delivered directly into it.

20 In the case where the discharge end of a sluice is on land, or otherwise accessible, the discharge itself may be arranged to operate a water-wheel or equivalent motor which supplies the power to operate the agitator.

25 Various modifications can be made to the apparatus, as will be obvious, without departing from the spirit or scope of the invention. For instance the frame may take a form other than that particularly described, and the cross-section of the agitator wire may be other than segmental, although a segmental cross-section is preferable, in that it tends more effectively to loosen the bed of material than some other sections of wire.

10 What I claim as my invention and desire to secure by Letters Patent is:—

1. In a gravity concentrator the combination of a stationary inclined concentrating 45 sluice, riffles therein extending across the sluice so as to cause the material to collect as an immersed bed therein, agitating elements which are shallow as compared with the depth of the riffles and are so positioned 50 within the sluice in close proximity to the bottom thereof as to extend transversely across the sluice and be embedded in a lower stratum only of the immersed bed of material between the riffles, and operating means 55 for the agitating elements whereby the latter may be gently reciprocated transversely to their length in the plane of said lower stratum so as to maintain the bed of material

loose throughout without having a stirring up effect on the material and without forming channels on the upper surface thereof, substantially as and for the purpose described.

2. In a gravity concentrator the combination of a stationary inclined concentrating 60 sluice, riffles therein extending across the sluice so as to cause the material to collect as an immersed bed therein, agitating elements which are shallow as compared with the depth of the riffles and are comprised of 65 bands of substantially segmental cross-section disposed with the flat face lowermost, the said agitating elements being positioned within the sluice in close proximity to the bottom thereof and extending transversely 70 across the sluice, being embedded in a lower stratum only of the immersed bed of material between the riffles, and operating 75 means for the agitating elements whereby the latter may be gently reciprocated transversely to their length in the plane of said lower stratum so as to maintain the bed of material loose throughout without having a stirring up effect on the material and without forming channels on the upper surface 80 thereof, substantially as and for the purpose described.

3. In a gravity concentrator for material carried in liquid suspension, the combination of a stationary inclined sluice along 85 which a pulp of the material to be concentrated flows, a plurality of riffles extending across the sluice at spaced intervals, thereby causing the material to collect as 90 immersed masses deepening from one end to the other, a plurality of agitating elements extending transversely across the sluice between adjacent riffles, said agitating elements 95 being positioned in close proximity to the bottom of the sluice and being shallow as compared with the depth of the riffles, whereby they are effective for agitating only the lowermost stratum of the immersed 100 masses between the riffles, and operating means for the agitating elements, said means being effective for gently reciprocating the agitating elements in the plane of said lower stratum and in a direction substantially parallel to the direction of 105 flow, thereby maintaining the lowermost stratum of the settled material in a relatively loose and unpacked condition without stirring up the material and without forming channels on the upper surface thereof.

110 In testimony whereof I affix my signature.
FRANK HERMAN COTHAY.
